CLAIM

The ornamental design for a pedicure chair, as shown and described.

DESCRIPTION

FIG. 1 is a top side perspective view thereof,
 FIG. 2 is a bottom side perspective view thereof,
 FIG. 3 is a front side view thereof,
 FIG. 4 is a back side view thereof,
 FIG. 5 is a left side view thereof,
 FIG. 6 is a top side view thereof; and,
 FIG. 7 is a bottom side view thereof.
 The right side is symmetrical to the left side.
 The broken lines shown illustrate portions of the pedicure chair that form no part of the claimed design.

1 Claim, 3 Drawing Sheets(56)
